FLATIRON

Wilbur F. Osler, Jr., Leonia, N. J.

Application September 12, 1946, Serial No. 696,408

7 Claims. (Cl. 38—74)

1

The present invention relates to ironing devices, and has special reference to flat-irons and ironing-boards of the type having magnetic means for increasing the pressure of the iron on the board.

The principal object of the invention is to provide devices of this character that are of simple, and durable construction, and convenient and efficient in use.

The invention is illustrated, by way of example, in the accompanying drawing, in which:

Figure 1 is a plan view of the ironing-board and flat-iron in their preferred form, the covering of the ironing-board being partly broken away;

Fig. 2 is a sectional elevation, on an enlarged scale and partly broken away, taken on the line 2—2 of Fig. 1;

Fig. 3 is a sectional elevation, taken on the line 3—3 of Fig. 2;

Fig. 4 is a sectional elevation similar to Fig. 2 of a modified form; and

Fig. 5 is a sectional view, partly in elevation, taken on the line 5—5 of Fig. 4.

In the construction illustrated in Figs. 2 and 3 of the drawings, the flat-iron is provided with a base 2 of magnetic material and a handle 4, and the ironing-board has a plurality of magnets 6 mounted therein so as to effect the desired magnetic attraction between the iron and the board. The iron may be heated by an electric heating element mounted in its base 2 and connected with terminal posts or studs 5.

In accordance with the present invention, an abutment member 8 of brass or other non-magnetic material is arranged in a recess in the underside of the flat-iron base 2. This abutment member 8 is provided with upstanding pins 10 that are mounted to slide in apertures in the base, and with a vertically extending post or rod 12 which may extend upwardly through an opening in the rear part of the handle 4. The upper end of this rod 12 is pivotally connected, by means of a rivet or pin, with the shorter arm of a lever 14 pivoted on a pin 16 in the handle. The lever 14 extends into a recess in the underside of the horizontal part of the handle, and the outer or longer arm of said lever 14 projects a distance below the underside of the handle so as to enable it to be conveniently engaged by the fingers of the user of the iron.

With this construction, upon pressing the longer arm of the lever 14 upwardly, said lever acts through the rod 12 and the abutment 8 to tilt the rear end of the iron upwardly from

the board. Such tilting of the flat-iron breaks the holding action of the magnets on the iron so as to enable the operator to easily lift the iron from the ironing-board. Thus it will be apparent that due to the leverage connection, irrespective of the pull of the magnets the operator may easily and quickly release the iron therefrom and lift the iron from the ironing-board. Upon releasing the lever 14 the magnetic attraction between the flat-iron and the board may again be established upon placing the iron on the board. It will be noted that the natural act of lifting the iron would cause the initial upward pressure of the fingers to act on the long arm of lever 14 to tilt the iron.

The magnets 6 are preferably permanent horseshoe magnets. As shown, they have their poles or ends extending upwardly through apertures 18 in the ironing-board which is made of non-magnetic material, the end surface of the magnets being substantially flush with the top surface of the board. The board may be provided with the usual fabric covering 20 which extends over the upper ends of the apertures 18 and the ends of the magnets.

In the illustrated ironing-board the magnets are mounted on a supporting plate 22 of non-magnetic material, they being secured in recesses in the plate by any suitable means such as by straps 24. The supporting plate 22 is adapted to be adjusted vertically to move the upper end surfaces of the magnets into the plane of or varying distances slightly below the top surface of the board. To provide for this, the supporting plate 22 is supported by means of suitable adjusting screws 26 whereby upon turning the screws the magnets may be moved vertically as desired.

By thus adjusting the vertical position of the magnets, the magnetic pull of the magnets on the flat-iron may be easily increased and decreased, and thus any desired degree of pressure may be employed without the use of heavy flat-irons.

In the form of flat-iron illustrated in Figs. 4 and 5, the handle of the iron is utilized as the lever for tilting the iron.

As shown, the rear end portion of the handle 28 is provided with a downwardly opening recess 30. Extending into this recess is a post 32 having its lower end secured to the base of the iron and having a pivot pin 34 at its upper end upon which the handle 28 is pivoted.

Also, extending upwardly into the recess 30 is a rod 36 which has its lower end secured to an abutment plate 38 that corresponds to the abut-

3

ment plate 8 of the form of iron first described. The upper end of this rod 36 is pivotally connected by a pin 40 with the handle 28, the pin being spaced a distance rearwardly of the pivot pin 34.

The front end of the handle 28 when the handle is in its normal ironing position as shown in full lines in Fig. 4 rests upon the top of the base of the iron. In order to firmly hold the front end of the handle from lateral movement while the iron is in use, the end of the handle is provided with a downwardly opening conical recess 42 which, when the handle is in ironing position, fits over a conical projection 44 on the base of the iron.

With this construction, when it is desired to remove the iron from the magnetic ironing-board, the natural act of lifting the iron swings the handle 28 upwardly and thus acts through the post 32 and the abutment member 38 to tilt the base of the iron so as to break the magnetic attraction. Upon replacing the iron on the ironing-board the weight of the iron retracts the abutment member 38, and through the rod 36 returns the handle to its normal ironing position.

Thus in this construction as well as in the construction shown in Figs. 2 and 3, the natural act of lifting the iron effects the desired tilting thereof, and upon replacing the iron on the ironing-board the weight of the iron serves to restore the parts to their normal positions.

As will be evident to those skilled in the art, my invention permits various modifications without departing from the spirit thereof or the scope of the appended claims.

As apparent from the drawings, in the form shown in Fig. 2 the movement of the lever 14 in a direction to tilt the iron is limited by the engagement of the top side 46 of the lever with the bottom wall 48 of the clearance recess in the handle 4. The movement of the handle in the opposite direction is limited by the engagement of the abutment or shoe 8 with the bottom wall 50 of the recess in the base 2 of the iron in which the shoe is received. In the form shown in Fig. 4, the turning movement of the handle in a direction to tilt the iron is limited by the engagement of the rear end or heel 52 of the handle 28 with the rear end extension 54 on the base of the iron. The movement of the handle 28 in the opposite direction is limited by the engagement of the abutment member or shoe 38 with the bottom wall 56 of the recess in the base of the iron which receives the shoe 38, and by the engagement of the underside 58 of the front end of the handle with the top surface 60 of the front end of the base of the iron. It will be apparent that in both constructions any other suitable arrangement of stops may be provided whereby when the iron has been tilted to a predetermined degree further upward pull on the lever arm 14 or handle 28 results in bodily lifting of the iron from the ironing-board, and upon release of the lever arm 14 or the handle 28, these parts are returned to their initial position with the shoes 8 and 38 respectively retracted.

This application is a continuation in part of my pending application Ser. No. 502,595, filed September 16, 1943, abandoned September 13, 1946.

What I claim is:

1. A flat-iron for use in connection with an ironing-board, comprising a base, a handle for the iron, a pivotal connection between the handle and said base having its axis arranged trans-

4

versely of the handle and positioned rearwardly of the portion of the handle normally grasped by the hand of the user in ironing, stops for respectively limiting the pivotal movements of the handle toward and from its normal ironing position whereby in lifting the iron from the ironing-board the forward arm of the handle is initially swung upwardly to the limit of the movement of the handle in said direction, an abutment member of non-magnetic material adapted to be moved above and below the bottom surface of said base, means for guiding the abutment member during its said movements, and connections between the abutment member and said handle for thus moving said abutment member during said pivotal movements of the handle respectively.

2. A flat-iron for use in connection with an ironing-board, comprising a base, a handle having its rear portion pivotally connected with the base whereby the handle may be swung toward and from its normal ironing position, stops for respectively limiting said pivotal movements of the handle, an abutment member of non-magnetic material adapted to be moved above and below the bottom surface of the base, means for guiding the abutment member during its said movements, and connections between the handle and the abutment member for thus moving said member during said movements of the handle.

3. A flat-iron comprising a base, a support on the base, a lever extending longitudinally between the heel and toe of the iron having its rear portion pivotally connected with said support to turn in opposite directions about a horizontal axis, stops for limiting such turning of the handle, an abutment member of non-magnetic material adapted to be moved above and below the bottom surface of the base, means for guiding the abutment member during its said movements, a member having one end connected with said abutment member and its other end pivotally connected with said lever at a point spaced rearwardly from the axis thereof whereby upon the user turning said lever to move the forward arm thereof upwardly by applying a lifting force thereto the iron is raised from the ironing-board and when said arm is released by the user while the iron is on the board the parts are returned to their initial positions.

4. A flat-iron for use in connection with an ironing-board, comprising a base, a handle for the iron, a lever pivoted on the handle between its ends with one arm thereof arranged to be engaged by the fingers beneath the handle, an abutment member of non-magnetic material adapted to be moved above and below the bottom surface of the base, means for guiding the abutment member during its said movements, connections between the abutment member and the other arm of said lever whereby when the iron is in ironing position on the board upon turning said lever in a direction to move said first mentioned arm upwardly the base is raised from the ironing-board, and stops for limiting the turning movement of said lever.

5. A flat-iron for use in connection with an ironing-board, comprising a base, a handle for the iron, a lever pivoted intermediate its ends to said handle having one arm arranged to be engaged by the fingers of the user when grasping the handle to turn the lever in one direction, an abutment member of non-magnetic material adapted to be moved above and below the bottom surface of the base, means for guiding the abut-

ment member during its said movements, connections between the abutment member and the other arm of said lever whereby when the iron is on the ironing-board upon turning the lever in said direction the iron is raised from the board and upon releasing the lever while the iron is on the board the parts are returned to their initial positions, and stops for limiting the turning movement of said lever.

6. A flat-iron comprising a base, a support mounted on the rear portion of the base, a lever having its rear portion pivotally mounted on said support with its forward arm spaced a distance above the base and arranged in position to enable a lifting force to be applied thereto by the fingers of the user to turn said lever to swing its said forward arm upwardly, an abutment member of non-magnetic material mounted in the rear portion of the base and adapted to be moved above and below the bottom surface of the base, a member connecting said abutment member with said lever at a point spaced rearwardly from the axis of the lever, whereby upon turning said lever in said direction the abutment member by engagement with the ironing-board causes the rear end of the iron to be raised so as to tilt the iron about the point of engagement of its forward end with the ironing-board, and when said forward arm is released while the iron is on the board, the parts are returned to their initial positions by the weight of the iron, stops for limiting the turning of the lever, and means for guiding the abutment member.

7. A flat-iron comprising a base having an upwardly extending support thereon, a handle for the iron pivotally connected near its rear end with

said support for limited upward movement from its normal ironing position as the user applies a lifting force to the handle to lift the iron from an ironing-board, stops for thus limiting the movement of the handle, an abutment member of non-magnetic material mounted for vertical movement with relation to the bottom of the base having its upper end pivotally connected with the handle at a point spaced a distance to the rear of the point of pivotal connection of the handle with said support so as to cause the lower end of the abutment member to be projected below the bottom of the base during said upward movement of the handle, and means for thus guiding the abutment member.
